ENGRAVING FACSIMILE SYSTEM

George Washington, Jr., Morristown, N. J.

Application February 8, 1947, Serial No. 727,407

7 Claims. (Cl. 178—6.6)

1

This invention relates to a method and machine for making reproductions, such as printing plates and mats, for use in forming printing press matrices, directly from a picture, form letter, map, drawing, etc., as well as from an ordinary black and white or colored photograph or transparency. Such a machine is disclosed in my Patent No. 2,179,002, granted November 7, 1939.

As set forth in said patent, there is provided a decomposing tool for making impressions in a printing plate. The decomposing tool forms a large number of impressions at high speed in the printing plate, the depth of the impression being a function of the opacity of the original picture. These varying depths thus form the light and shadow counterparts of the picture. It will be readily understood that the above method of reproducing a picture depends for its integrity upon the uniform spacing of the impressions so that the only variable introduced is the depth of impression. If, in addition, the points of impression were unequally spaced, such unequal spacing would introduce a second variable which would seriously affect the reproduction, because the unequal spacing would provide a shade wave pattern throughout the reproduced picture which is not part of the original picture. Such unequal spacing would obscure places that should be clear and would provide clear spaces for portions that should be obscure. The equal spacing of the points of impression is thus a highly desirable, fundamental object in any reproduction system of this type.

It is therefore the principal object of this invention to provide a method and means for insuring equal spacing of the points of impression throughout the area of picture reproduction.

It is still another object of this invention to provide means for equally spacing the points of impression regardless of the relative speed of operation of the impressing tool or of the carriages upon which the original picture and the reproduction are mounted.

Still other objects and advantages of this invention will become apparent in the following detailed description thereof.

In the accompanying drawings,

Fig. 1 is a plan view, with parts broken away, disclosing an assembly of the mechanism constituting one form of my invention.

Fig. 2 is a wiring diagram of a mixer amplifier employed in the Fig. 1 device.

Fig. 3 is an end view of the impression spacing control member, only a few of the teeth being

shown and the remainder of the teeth being indicated diagrammatically.

Fig. 4 is a side elevation, partly sectioned vertically, of the Fig. 3 device.

Figs. 5 and 5A are two enlarged views of a portion of the control member of Fig. 3 showing the teeth in the two limiting position.

The mechanism which is illustrated in the drawings and which constitutes one embodiment of my invention, consists primarily of two fundamental parts, namely a fixed base-plate 10 and a movable carriage 11 mounted to slide on guides or runners 12. Upon the fixed base-plate 10 there is mounted the driving mechanism consisting of a motor M which rotates two cylinders 20 and 20' in 1:1 relationship through reduction gearing such as that contained in reduction gear box 21 and driving a pair of gears 22, 23 fixed to the shafts 24, 25 upon which the cylinders 20 and 20', respectively, are mounted. The said shafts 24, 25 are journalled in bracket 26 supported on base-plate 10. The shaft 25 may be additionally supported at its opposite end in bracket 27, also fixed to the base-plate 10.

The picture, printed matter or other translucent representation 30 is wrapped around the cylinder 20 and held thereon by any suitable clamping means (not shown), and the printing plate 30' is wrapped around cylinder 20' and fixed thereon by any suitable clamping means (not shown). The reproduction of the picture 30 upon the print plate or matrix 30', which in this case is a black and white transparency, is performed as follows: For this purpose the cylinder 20 is a hollow transparent cylinder, preferably of glass, as shown, and a beam of light is designed to be reflected through the wall of the cylinder to the surface of the transparency 30 so that the amount of light which passes through the transparency will vary in accordance with the opacity of that point. For this purpose, there is mounted upon the carriage 11 a source of light L provided with an optical system 31 designed to cause a beam of light to be thrown upon a condenser lens 32, which converges the beam upon a mirror 33 fixed in a sleeve 34 slidably within the hollow cylinder 20. The said sleeve 34 is provided with a cut-out portion 35 through which the reflected beam of light may pass. The optical system is such that the beam of light is focused at 36 upon the transparency 30. The amount of light passing through the transparency depends upon the opacity of the transparency at that point, and the quantity of

light so determined is caused to be transmitted

into a lens system 37 where, by a suitable optical system, the light is focused upon a light-sensitive cell 38 to vary the amount of current which passes through the cell. This current after passing through a mixer amplifier (to be described more in detail hereinafter) is suitably amplified by any standard amplifier and may be caused to operate a dynamic unit 29 as shown in Fig. 1 to cause the armature 39 thereof to be repelled to a greater or less extent to cause an engraving tool in the form of a needle or tip 40 normally lying closely adjacent to the surface of the print plate or matrix 30' to be pressed into said print plate to a greater or less degree depending upon the quantity of light that has passed through the corresponding point of the transparency 30. The position of tool 40 may be controlled by adjusting the dynamic unit which is mounted on the carriage on guide rods 29' for movement toward or away from roller 20'. The dynamic unit may be fixed in position by any suitable clamping means (not shown).

Tool 40 may be a cutting tool or a compressing tool, but I prefer to provide means whereby the tip 40 actually destroys the material of the print plate to a greater or less degree, depending upon the degree of movement of tool 40 into the print plate. Such destruction is preferably accomplished by heating the tool 40 in conjunction with the proper selection of material comprising the print plate 30' so that said material will be destroyed by heat. Thus I have provided a heating coil 41 supplied with current from any suitable source of current, to cause the said tool 40 to be maintained at a temperature of at least 600 or 700 degrees. The material comprising the plate 30' may be any kind that will be decomposed by heat, and for this purpose a nitro-Celluloid matrix has been found satisfactory. The point 43 of tool 40 is conical, tapering toward the print plate, so that the degree to which the said point enters the matrix will control the amount of material which is decomposed and removed. There is thus formed in the plate a depression whose depth and surface area are functions of the amount of light which has passed through the corresponding point of the transparency 30.

It will now be apparent that if the light from light source L can be caused to scan the surface of transparency 30, and the cone tip 43 can be caused to remove material at corresponding points on print plate 30' in proportion to the light passing through transparency 30, there will be obtained upon the printing plate 30' a reproduction of the picture or image on the transparency 30. It will, of course, be appreciated that the greater the number of points and the closer they are located the better will be the reproduction on the print plate 30'. For accomplishing this result, I provide means for causing the spot of light 36 to traverse a spiral path of very fine pitch completely covering the surface of transparency 30. The spiral path of light-spot 36 is effected by causing the carriage 11 upon which the source of light L, optical system 31 and sleeve 34 with its optical systems 32 and 33 are mounted, to be moved in translation while the sleeve 34 is rotated. The translatory movement of carriage 11 upon baseplate 10 may be effected from reduction gearing 21 driving through gears 22, 23 to further reduction gearing 44, 45 to rotate shaft 46 journaled within the standards 26 and 27, to rotate a worm 47. The said worm is threaded through a bearing 48 fixed to the carriage 11 so that as the worm rotates the carriage

is moved in translation. The carriage 11 thus carries sleeve 34 in a linear direction within the hollow cylinder 20. The dynamic unit and the tip 40 being supported on carriage 11 are moved correspondingly in translation.

At the same time that the sleeve 34 is being moved in translation, the cylinder 20 is being rotated, as hereinbefore described. Therefore the point of light 36 traverses a spiral path on the surface of transparency 30. At the same time the tool 40 moving in translation and the cylinder 20' rotating, causes the tool to traverse a spiral path relative to the print plate 30' in synchronism with the spiral path traversed by point of light 36.

The light which issues from light cell 38 is thus continuous, varying only in intensity. If this light were received uninterruptedly by dynamic unit 29, the decomposing tool 40 would trace a continuous helical line and thus provide nothing more than streaks. In order that the picture may be reproduced it is necessary to interrupt the varying current delivered to dynamic unit 29. Such interruption must occur at a frequency which is high relative to the frequency of rotation of the cylinder 20', for example, of the order of 600 cycles per second and, furthermore, such interruptions must be so controlled that the impressions made by tool 40 will be equally spaced around the circumference of the printing plate 30' for the reasons noted in the introduction hereto. Such equal spacing of impressions becomes a serious problem in the face of variations in speed of the cylinders 20 and 20'. Therefore, I have provided the following solution for this problem:

Upon one end of shaft 25 of the cylinder 20' which carries the printing plate 30', I provide a metallic disc 50 whose periphery is notched to form a large number of teeth 51. All of the notches (and, hence, also the teeth) are of exactly the same length and depth and are spaced apart exactly equal increments of linear distance along the periphery of the disc, and, hence, are spaced apart equal angular distances relative to the center of the disc. The disc 50 is concentrically positioned with respect to a fixed, metallic annulus 52 whose inner periphery is similarly notched at equal angular distances with respect to the center of disc 50 to provide the same number of teeth 53 as there are teeth 51. Furthermore, I form disc 50 and annulus 52 as the two plates of an electric condenser so that the capacity of said condenser will vary from maximum when the teeth are in alignment as shown in Fig. 5, to minimum when the teeth are completely out of alignment, as shown in Fig. 5A. By providing an electrical system whereby current will be delivered from light cell 38 to the dynamic unit 29 only when the teeth 51 and 53 are in alignment to yield the maximum capacity, I provide a system whereby the decomposing tool 40 is actuated each time disc 50 has rotated an angular distance equal to the distance between adjacent teeth. Thus, it will be seen that tool 40 will make as many impressions in the printing plate 30' per revolution of cylinder 20' as there are teeth on the periphery of disc 50 and on the internal surface of annulus 52. Thus the number of actuations of tool 40 per revolution of cylinder 20' is constant and the spacing between adjacent impressions is necessarily constant regardless of the speed of cylinder 20' or variation in such speed since the actuation of tool 40 depends only upon the angular displacement of disc 50 and not upon rate of motion.

For accomplishing the above result, reference may be had to Fig. 2 wherein it will be seen that light cell 38 is continuously applying its voltage to the second grid 60 of an electron tube 61 which has an anode 62, a cathode 63 and a suppressor grid 64. The variations in voltage applied to the second grid 60 do not result in an output from the plate 62 because of the bias normally placed upon the first grid 65 which is in electric communication with the condenser 50, 52. However, when the teeth of disc 50 are in alignment with the teeth of annulus 52 the first grid 65 is biased sufficiently in the proper direction to permit an output from the plate 62. Therefore current of an intensity determined by the current output of light cell 38 at that particular instant will pass out of the mixer-amplifier and after being amplified by the power amplifier will be applied to the dynamic unit 29 and decomposing tool 40. As soon as the teeth move out of full alignment, tube 61 again becomes non-conductive and the current is shut off until disc 50 has moved through an angular distance sufficient to bring its teeth again in alignment with the teeth of the annulus 52.

Thus absolutely equal spacing between impressions on printing plate 30' must result since they are controlled only by the angular displacement of disc 50 relative to annulus 52 and this angular displacement is independent of any variations in speed.

As shown in the sectional part of Fig. 4, the elements 50 and 52 forming the condenser plates are metallic. The annulus 52 may be supported on bracket 70 from which it is insulated by suitable insulation 71. The bracket 70 is fixed to the base plate 10 and may also support an additional bearing 75 for the shaft 25.

The foregoing description of the invention is merely illustrative and changes may be made within the scope of the appended claims.

Having described my invention, what I claim and desire to secure by Letters Patent is:

1. A device for making printing plates directly from a subject to be reproduced comprising: means for scanning the subject with a beam of light, a light-sensitive cell in the path of the beam of light, a rotatable cylinder, a printing plate carried by said cylinder, an image-forming tool normally disposed in inoperative position with respect to the printing plate, means for relatively moving the printing plate and the tool to scan said printing plate in synchronism with the subject scanning means, a variable condenser, means for cyclically varying the capacity of the condenser throughout a plurality of cycles for each revolution of the said cylinder, pulsing means controlled by the condenser for rendering the said tool operative with respect to said plate only during preselected values of the cyclically varying capacity, and means for causing the tool to make an impression in the printing plate in response to the quantity of light striking the light-sensitive cell when the pulsing means renders the said tool operative with respect to the said plate.

2. The invention as recited in claim 1, wherein the condenser comprises, a metallic annulus having a plurality of spaced teeth, a metallic disc concentric with said annulus and having a plurality of similar teeth corresponding to and spaced from the teeth on said annulus, and means electrically insulating the said disc from said annulus.

3. The invention as recited in claim 2, wherein

the said disc and the plate-carrying cylinder are secured to a common shaft.

5 4. A device for making printing plates directly from a subject to be reproduced comprising: a rotatable cylinder carrying the subject; a light beam cooperating with the said subject; means for causing said light beam to traverse a helical path to scan the subject; a light-sensitive cell in the path of the light beam; a second cylinder and a metallic disc affixed to a common rotatable shaft, said disc having a plurality of spaced teeth; a printing plate carried by the second cylinder; a metallic annulus concentric with the said disc and having a plurality of teeth corresponding to and spaced from the teeth on the said disc; means electrically insulating the disc from the annulus; an image-producing tool; means for relatively moving the printing plate and the tool to scan the said plate in synchronism with the light scanning means; means for causing the tool to penetrate the printing plate in response to the quantity of light falling on the light-sensitive cell; and means effective to prevent the tool from penetrating the printing plate 15 when the teeth on the said disc and annulus are out of alignment.

20 5. A device for making reproductions on printing plates directly from a subject to be reproduced comprising, means for scanning the subject with a light beam, a light-sensitive cell producing electrical variations in accordance with variations 25 in the light beam, a rotatable cylinder, a printing plate carried by said cylinder, an image-forming tool, means for relatively moving the plate and the tool in synchronism with the light beam scanning the subject, an electron tube having an anode and a plurality of grids cooperating with a cathode, an output circuit connected to the said anode, a first control grid normally biased to block conduction between the cathode and the anode, a disc rotatable with said rotatable cylinder said disc having a plurality of teeth, an annulus having a plurality of teeth corresponding to and spaced from the teeth on the disc, means electrically insulating the disc from the annulus, circuit elements connecting the disc and annulus between a voltage source and the first control grid of the electron tube to produce a pulsating flow of current in the said output circuit as the teeth on the disc and annulus move into and out of alignment, circuit elements for impressing the electrical variations produced by the light-sensitive cell upon a second control grid to thereby modulate the amplitude of the current which flows in the said output circuit, and means for causing the tool to penetrate the plate in accordance with the modulated current flowing in the said output circuit.

25 6. A device for making printing plates directly 30 from a subject to be reproduced comprising, means for scanning the subject with a light beam, a light-sensitive cell in the path of the light beam, a rotatable shaft, a cylinder secured to the rotatable shaft a printing plate carried by 35 the cylinder, an image-forming tool normally spaced from the printing plate, means for relatively moving the printing plate and the tool to scan the said plate in synchronism with the subject scanning means, a metallic disc secured to the said rotatable shaft and having a plurality of circumferentially-spaced teeth, a metallic annulus concentric with the disc and having a plurality of teeth corresponding to and spaced from the teeth on the disc, means electrically insulating the annulus from the disc, tool-operat-

ing means, means for causing the tool-operating means to impart an oscillatory movement to the tool toward and away from the printing plate as the teeth on the said disc and annulus move into and out of alinement, and means for modulating the amplitude of the said oscillatory movement of the tool to cause the tool to penetrate the printing plate in response to the variations of the light striking the light-sensitive cell.

7. In a picture reproducing device of the character wherein an image-forming tool is adapted to penetrate a printing plate in accordance with variations in a beam of light scanning the subject to be reproduced, the combination of a rotatable shaft, a cylinder secured to the shaft, a printing plate carried by the cylinder, an image-forming tool normally disposed in inoperative position with respect to the printing plate, tool-operating means for moving the tool toward the printing plate to render the tool operative with respect to the said plate, a disc secured to the rotatable shaft and having a plurality of spaced teeth,

an annulus concentric with the disc and having a plurality of teeth corresponding to and spaced from the teeth on the disc, means electrically insulating the disc from the annulus, and means controlled by the said disc and annulus for periodically actuating the tool-operating means to render the tool alternately operative and inoperative with respect to the printing plate as the teeth on the disc and annulus move into and out of alinement.
